CEMENT CLINKER CHAMBER OR THE LIKE

Harry S. Lee, Detroit, Mich.

Application February 13, 1932. Serial No. 592,773

19 Claims. (Cl. 222—5)

My invention relates to fluid cooling valve or gate mechanism of the character described.

An object is to provide valve or gate apparatus adapted particularly for use in conjunction with heated materials which come in direct contact therewith and which are of an abrasive character and wherein the valve apparatus is employed in a chamber through which such heated materials are passed and wherein the temperature is very high. Specifically, an object is the provision of valve mechanism of this character adapted for use in the cooling chamber of a cement mill wherein heated cement clinker is impelled through the chamber and comes directly into contact with the valve mechanism.

My improved mechanism is so constructed and arranged that it may be readily cooled so as to be maintained at a non-destructive temperature and any tendency toward buckling or warping due to heat is minimized and replacement of parts is relatively easily made.

Other objects and advantages of my improved construction will more fully appear from the following specification, appended claims, and accompanying drawings wherein:

Fig. 1 is an elevation partly in section of a chamber provided with my invention.

Fig. 2 is a cross sectional view taken on 2—3 of Fig. 1.

Fig. 3 is a cross sectional view through the hollow shaft,

Fig. 4 is a cross sectional view through the hollow shaft and valve flap,

Figs. 5, 6, and 7 are cross sectional views taken on lines 5—5, 6—6, and 7—7, respectively, of Fig. 3, and

Fig. 8 is an elevation of a fragment of the outer end of the valve flap member.

Figs. 1 and 2 show a construction wherein my valve mechanism is mounted and associated. The specific construction shown is that of the cooling chamber for cement clinker. In Fig. 1 this chamber is indicated generally as 10. It has a clinker intake 12 and an air exhaust 14.

45 The inner wall is formed of refractory 16, as shown. The chamber is jacketed and has an outer wall 18. The space between the inner and outer walls serves as an air passageway. There is a grate 20 over which travels a drag chain 22 which is shown as supported at one end by a drive sprocket 24 and which enters through an opening 26 in the wall of the chamber. Sealing mechanism 28 is shown at this opening 26. Air inlets 30 are provided which discharge into the 55 chamber underneath the grate and through

which a current of air is directed to cool the clinker carried through the chamber. The clinker is indicated at 32.

In a construction of the general type above specified I provide valve mechanism. This valve mechanism is shown in detail in Figs. 3 to 8, inclusive. It is shown in general assembly and in cross section in Figs. 1 and 2. Only one of the sections is here shown though a plurality would normally be provided. This valve comprises a hollow shaft illustrated in section in Fig. 3 and indicated generally by the numeral 34. This hollow shaft extends through the refractory inner wall 16 and is journaled in the outer wall 18 of the chamber as shown in Fig. 2. One end of the hollow shaft is connected with a suitable source of fluid under pressure. This fluid might be air. It receives fluid from such source which enters the shaft. The other end of the shaft may be connected to a suitable desirable apparatus. This might be the piping about the chamber and which might lead back to a cement kiln not shown in the drawings. The end of one shaft may be provided with a suitable counterweight 36 to hold the valve or gate at a determined position within the chamber. It will be seen that this counterweight holds the valve against the heated material or cement clinker so that it not only divides the chamber into compartments but serves to level off this material.

The valve proper comprises, in addition to the hollow shaft 34, a plurality of hollow valve flap sections 38, three being here shown. These sections are arranged side by side on the shaft and are secured to a flange portion thereof by bolts 40, as shown particularly in Figs. 3 to 7, inclusive. The flattened flange portion is indicated as 42 and appears specifically in Fig. 3. Each section is provided with a dividing baffle wall 44 extending lengthwise thereof from the shaft toward the outer end of the section. It will be seen that the shaft itself is provided with a longitudinally extending dividing wall 46 which is so arranged as to divide the shaft into two compartments. The space on one side of the dividing wall communicates with one end of the shaft. The space on the other side of the dividing wall communicates with the other end of the shaft. Each section communicates with the shaft through two apertures. One aperture is indicated as 48 and this leads from the shaft on one side of the dividing wall into the adjacent section. The other aperture is indicated as 50

110

and this leads into the shaft on the opposite side of the dividing wall from each section.

The sections are provided at their outer ends with a wear resisting shoe element 52 illustrated particularly in Figs. 4, 5, and 8. This has a rounded upwardly extending portion which covers the lower part of the forward wall of each section and the shoe extends across the outer ends of the three sections closing them and being in direct communication with the interior of the sections. The shoe element is removable and may be held in place as indicated in Figs. 5 and 8. Bolts 54 may be provided for the purpose shown.

15 It will appear that the cooling fluid entering the shaft at one end will pass into the several sections through the apertures 48 so that fluid of substantially the same temperature will enter each section and will pass out of the several sections through the apertures 49 into the shaft on the opposite side of the dividing wall and be exhausted from the opposite end of the shaft. Using a plurality of sections of this type makes replacement relatively simple and minimizes the 25 possibility of buckling or warping and tends to provide substantially the same temperature throughout the entire valve gate structure.

A pair of coils 56 encircles the shaft 34 between the walls 16 and 18. These coils are held 30 apart by springs 58 so as to form a closure above the shaft adjacent the inner wall as is more specifically described in a copending application #592,774 this day filed. The structure of the sealing mechanism for the chain at the opening 35 through the chamber wall is likewise defined in a copending application #592,772 of this inventor of even date and the general construction of the chamber as here provided is likewise defined in an application of this inventor of even date.

40 Reference is likewise herein made to my copending application Serial No. 543,416 wherein the broad features of my invention herein partially disclosed are described and claimed.

What I claim is:

45 1. The combination in a chamber through which heated material is adapted to be impelled, of valve mechanism suspended for swinging movement within said chamber and comprising a tubular shaft extending through the walls of 50 the chamber, a tubular valve flap removably carried by said shaft and communicating with the interior of the shaft, and a shoe of heat resisting material removably secured to the outer end of said valve flap in direct communication with 55 the interior thereof.

2. The combination in a chamber through which heated material is adapted to be impelled and which is provided with means for impelling such material therethrough, of valve mechanism 60 suspended for swinging movement within said chamber and comprising a tubular shaft extending through the walls of the chamber, fluid carrying means communicating with each end of the shaft beyond the wall of the chamber, a 65 hollow valve flap carried by said shaft and communicating therewith to receive fluid therefrom, and a shoe of heat resisting material removably secured to the outer end of said valve flap in direct communication with the fluid in the interior thereof.

70 3. The combination in a chamber through which heated material is adapted to be passed of valve mechanism suspended for swinging movement within said chamber and comprising a 75 tubular shaft extending through the walls of the

chamber, a hollow valve flap carried by said shaft and communicating therewith, and a heat resisting shoe secured to the outer end of said valve flap and having a protective portion extending upwardly on one face of the valve flap 80 from said outer end.

4. The combination in a chamber through which heated material is adapted to be passed of valve mechanism suspended for swinging movement within said chamber and comprising a tubular shaft extending through the walls of the chamber, means for delivering cooling fluid into one end of said hollow shaft and for receiving the same from the opposite end, a tubular valve flap removably carried by said shaft and communicating therewith, and a heat resisting shoe removably secured to the outer end of said tubular valve flap closing the same and forming an abrasive resisting wear plate for said outer end.

90 5. The combination in a chamber through which heated material is adapted to be passed of valve mechanism suspended for swinging movement within said chamber and comprising a tubular shaft extending through and journaled 100 within the walls of the chamber, means for delivering cooling fluid into one end of the shaft and for receiving the same from the opposite end, a valve flap secured to said shaft and comprising a plurality of tubular sections arranged in a line 105 on said shaft and each section communicating with the interior of said shaft to receive cooling fluid therefrom, and a wear resisting shoe secured as a closure over the outer ends of said flap sections.

110 6. The combination in a chamber through which heated material is adapted to be passed of valve mechanism suspended for swinging movement within said chamber and comprising a tubular shaft carried by the wall of the chamber, 115 means for delivering cooling fluid into said hollow shaft and for receiving the same therefrom, a valve flap secured to said shaft and comprising a plurality of hollow sections arranged side by side on said shaft, each section provided with a 120 baffle plate extending from the shaft through the section toward the shoe, each section communicating on one side of the baffle plate with the interior of the hollow shaft to receive cooling fluid therefrom and with the interior of the shaft on 125 the opposite side of the baffle plate to discharge said fluid back into the shaft, and a dividing wall extending lengthwise through the hollow shaft and with the discharge openings from the shaft to the hollow flap sections arranged on one side 130 of said wall and the inlet openings to the shaft from the hollow flap sections arranged on the opposite sides of the wall.

7. The combination in a chamber through which heated material is adapted to be passed, of 135 valve mechanism suspended for swinging movement within the chamber comprising a tubular shaft divided by a wall extending longitudinally from one side adjacent one end of the shaft to the opposite side adjacent the opposite end of the 140 shaft, and a hollow valve flap member carried by the shaft and communicating therewith on both sides of the dividing wall.

8. The combination in a chamber through which heated material is adapted to be passed, of 145 valve mechanism suspended for swinging movement within the chamber comprising a tubular shaft divided by a wall extending from one side adjacent to one end of the shaft longitudinally of the shaft to the opposite side adjacent to the 150

opposite end, a source of cooling fluid communicating with one end of the shaft, and a hollow valve flap member carried by said shaft and communicating therewith on one side of the dividing wall to receive cooling fluid therefrom and communicating therewith on the opposite side of the dividing wall to discharge fluid back into the shaft.

9. The combination in a chamber through which heated material is adapted to be impelled and which is provided with means for impelling such material therethrough, of valve mechanism suspended for swinging movement within said chamber and comprising a tubular shaft communicating at one end with a source of cooling fluid and adapted to discharge the same from the opposite end and provided with a dividing wall separating the interior of the shaft into two longitudinal compartments one communicating with one end of the shaft and the other communicating with the opposite end of the shaft, a hollow valve flap member carried by said shaft and provided with a baffle wall dividing the same into two compartments, one compartment communicating with the interior of the shaft on one side of its dividing wall to receive cooling fluid therefrom and the other compartment communicating with the interior of the shaft on the opposite side of its dividing wall to discharge said fluid back into the shaft.

10. The combination in a chamber through which heated material is adapted to be passed of valve mechanism suspended for swinging movement within said chamber and comprising a tubular shaft extending through and journalled within the walls of the chamber, said shaft having a dividing wall extending from one side at one end to the opposite side at the opposite end, means for delivering cooling fluid into one end of said hollow shaft and for receiving the same from the opposite end, a plurality of tubular valve flap sections arranged end to end on said shaft, each section having a baffle wall extending from the shaft at one end to a point spaced slightly from the opposite end and each communicating on one side of the baffle wall with the interior of the shaft on one side of the dividing wall to receive cooling fluid therefrom, and communicating on the opposite side of the baffle wall with the interior of the shaft on the opposite side of the dividing wall, and a wear resisting shoe secured over the outer ends of said flap sections closing the same.

11. The combination in a chamber through which heated material is adapted to be passed of valve mechanism suspended for swinging movement within said chamber and comprising a tubular shaft extending through the walls of the chamber, said shaft provided with a dividing wall extending from one side at one end to the opposite side at the opposite end, a cooling fluid conduit communicating with each end of the shaft, a plurality of hollow valve flap sections arranged in a line on said shaft, each section provided with a baffle wall extending from the shaft through the section toward the shoe, and each section communicating on one side of its baffle wall with the interior of the hollow shaft on one side of its dividing wall to receive cooling fluid therefrom and communicating on the opposite side of its baffle wall with the interior of the shaft on the opposite side of its dividing wall to discharge said fluid back into the shaft.

12. The combination in a chamber through which heated material is adapted to be passed,

of valve mechanism suspended for swinging movement within the chamber comprising a tubular shaft divided longitudinally by a dividing wall so arranged that the interior of the shaft on one side of the wall communicates with one end of the shaft and the interior of the shaft on the opposite side of the wall communicates with the other end of the shaft, a source of cooling fluid communicating with one end of the shaft, and a plurality of hollow valve flap sections arranged in a line on said shaft, each section communicating with the shaft on each side of its dividing wall.

13. The combination in a chamber through which heated material is adapted to be passed, of valve mechanism suspended for swinging movement within the chamber comprising a tubular shaft divided longitudinally by a dividing wall so arranged that the interior of the shaft on one side of the wall communicates with one end of the shaft and the interior of the shaft on the opposite side of the wall communicates with the other end of the shaft, a source of cooling fluid communicating with one end of the shaft, a plurality of tubular valve flap sections arranged in a line on said shaft, each section communicating with the shaft on each side of its dividing wall, and a removable wear plate secured to the outer ends of said sections closing the same.

14. The combination in a chamber through which heated material is passed of a valve comprising a hollow shaft journalled in the walls of the chamber and extending therethrough, a fluid conduit communicating with each end of the shaft, said shaft provided with an interior dividing wall extending from one side of the shaft at one end to the opposite side of the shaft at the opposite end, a hollow valve flap secured to said shaft and having a baffle wall extending from the end adjacent to the shaft toward the opposite end, said valve flap communicating on opposite sides of its baffle wall with the interior of the shaft on opposite sides of its dividing wall.

15. The combination in a chamber through which heated material is passed of a valve comprising a hollow shaft journalled in the walls of the chamber and extending therethrough, a fluid conduit communicating with each end of the shaft, said shaft provided with an interior dividing wall extending from one side of the shaft at one end to the opposite side of the shaft at the opposite end, a tubular wall flap detachably secured to said shaft and having a baffle wall extending lengthwise therethrough, the interior of said flap communicating on opposite sides of its baffle wall with the interior of the shaft at the opposite sides of its dividing wall, and a cone resisting shoe closing the outer end of the tubular valve flap.

16. The combination in a chamber through which heated material is passed of a valve comprising a hollow shaft journalled in the walls of the chamber and extending therethrough, a fluid conduit communicating with each end of the shaft, said shaft provided with an interior dividing wall extending from one side of the shaft at one end to the opposite side of the shaft at the opposite end, a tubular wall flap detachably secured to said shaft and having a baffle wall extending lengthwise therethrough, the interior of said flap communicating on opposite sides of the baffle wall with the interior of the shaft at the opposite sides of its dividing wall, and a channel shaped wear resisting shoe closing the outer end of the

tubular valve flap and having a portion extending upwardly over the lower portion of one side of the valve flap.

17. The combination in a chamber through which heated material is passed of a valve comprising a hollow shaft journalled in the walls of the chamber and extending therethrough, a fluid conduit communicating with each end of the shaft, said shaft provided with an interior dividing wall extending from one side of the shaft at one end to the opposite side of the shaft at the opposite end; said shaft provided with longitudinally extending flanges on opposite sides, a hollow valve flap detachably secured to said flanges and provided with an interior baffle wall extending from the shaft to a point spaced from the opposite end of the interior thereof, the interior of said flap section communicating on opposite sides of its baffle wall with the interior of the shaft on opposite sides of its dividing wall.

18. The combination in a chamber through which heated material is passed of a valve comprising a hollow shaft journalled in the walls of the chamber and extending therethrough, a fluid conduit communicating with each end of the shaft, said shaft provided with an interior dividing wall extending from one side of the shaft at one end to the opposite side of the shaft at the opposite end, a tubular valve flap detachably secured to said walls and provided with a

baffle wall extending on the shaft toward the opposite end dividing the interior into two compartments, the interior of said flap communicating on opposite sides of its baffle wall with the interior wall on the shaft and on opposite sides of the dividing wall, and a concave-convex shoe portion detachably secured to the end of the tubular flap closing the same.

19. The combination in a chamber through which heated material is passed of a valve comprising a hollow shaft journalled in the walls of the chamber and extending therethrough, a fluid conduit communicating with each end of the shaft, said shaft provided with an interior dividing wall extending from one side of the shaft at one end to the opposite side of the shaft at the opposite end, a tubular valve flap detachably secured to said walls and provided with a baffle wall extending on the shaft toward the opposite end dividing the interior into two compartments, the interior of said flap communicating on opposite sides of its baffle wall with the interior wall on the shaft and on opposite sides of the dividing wall, and a concave-convex shoe portion detachably secured to the end of the tubular flap closing the same, said shoe being interlocked with the flap section on one side and secured by connecting means to the flap section on the opposite side.
